BURNER

Carl A. Borland, Chicago, Ill., assignor to Western Electric Company, Incorporated, New York, N. Y., a corporation of New York

Application May 11, 1935, Serial No. 20,979

7 Claims. (Cl. 158—116)

This invention relates to a burner, and more particularly to a piloted gas burner.

In some industrial plants gas is purchased at a price based on a maximum demand for a given period and when an amount of gas equal to the fixed maximum demand has been consumed, gas may be generated at the plant to avoid paying a premium price above the maximum demand price. The generated gas, however, may have a different rate of flame propagation than the purchased gas and will therefore not burn effectively in some types of burners.

An object of the present invention is to provide an effective and efficient burner having a wide range of utility.

In accordance with one embodiment of the invention a burner is provided having a main flame orifice surrounded by a plurality of auxiliary flame orifices from which gas issues at a rate increasing with their proximity to the main flame.

Other objects and advantages will appear as the description proceeds.

A complete understanding of the invention may be had by referring to the following description taken in conjunction with the accompanying drawing, in which

Fig. 1 is a longitudinal section of a burner nozzle embodying the invention;

Fig. 2 is an end view of the burner nozzle shown in Fig. 1;

Fig. 3 is a longitudinal section of a modified form of burner nozzle;

Fig. 4 is an end view of a burner nozzle shown in Fig. 3;

Fig. 5 is a longitudinal section of a further modification of the invention;

Fig. 6 is an end view of the modification of the burner nozzle shown in Fig. 5;

Fig. 7 is a longitudinal section of a still further modification of the invention, and

Fig. 8 is an end view of the burner shown in Fig. 7.

Referring now more in detail to the drawing and particularly to the embodiment of the invention shown in Figs. 1 and 2, a conduit 11 is shown which may be directly or indirectly connected to a source of combustible gas and is usually provided with a valve (not shown) for regulating the amount of gas supplied to a nozzle 12. The nozzle 12 has a central orifice 13 of relatively short length so as to emit gas at a high velocity to produce a main flame 14. Extending radially from the orifice 13 is a plurality of series of auxiliary flame orifices 15. The inner orifice 15 of each of

the series is slightly longer than the orifice 13 and of considerably smaller cross-section and each succeeding orifice of each series is relatively longer than the preceding one, the longest orifice of each series being the one adjacent the periphery.

In the embodiment of the invention shown in Figs. 1 and 2 the auxiliary orifices 15 are all of equal cross-section. However, the inner orifice will emit gas at a considerably higher velocity than the outer orifices adjacent the periphery and the velocity of gas emitted from the intervening orifices will progressively decrease from the inner orifice to the outer orifice of each series. When the main flame is burned from the orifice 13 the position of the flame will vary with the velocity of the gas and the rate of flame propagation of the gas used. That is, with one type of gas the flame 14 may extend from its tip to the point where the gas issues from the orifice 13, while with a gas of a lower rate of flame propagation the flame 14 may not begin until some point spaced from the orifice 13. When the flame does not extend down to the orifice 13 there is danger that the flame may leave the nozzle completely and be extinguished. To prevent such a contingency the auxiliary flame orifices are provided. Since the gas issues more slowly through the auxiliary orifices the flame even of the inner orifice of each series may extend down to the end of the orifice, and even though a gas of a slow rate of flame propagation is passed through the auxiliary orifices at a high rate, the flames of the outer orifices at least will always begin from immediately at the end of the orifice so that there is no danger at any time that all of the flames will leave the nozzle and be entirely extinguished. A burner of this type may be used with ordinary manufactured gas for certain periods of the day and when there is danger of exceeding the maximum demand rate for the gas, the burner may be connected to a different source of gas, such as compressed liquefied gases which are well known on the market, to keep the cost of operating the burner at a minimum.

Figs. 3 and 4 illustrate a modified form of the invention in which the burner nozzle is provided with a central aperture 16 for the main flame which is surrounded by a plurality of radially extending slots 17. The slots 17 are of progressively increasing length toward the outer periphery of the nozzle so as to restrict the flow of gas most at the periphery of the nozzle. The effect of this will be similar to the effect de-

scribed in connection with the embodiment of the invention shown in Figs. 1 and 2.

Figs. 5 and 6 illustrate an embodiment of the invention having a central aperture 18 for the main flame and a plurality of radially extending apertures 19 which are all of the same length but vary in cross-section, the apertures adjacent the main flame aperture 18 being of largest cross-section and progressively decreasing to the apertures adjacent the periphery.

Figs. 7 and 8 illustrate an embodiment of the invention having a star-shaped aperture 21 which in effect forms a central main flame orifice surrounded by a plurality of wedge-shaped slots 15 which restrict the flow of gas least adjacent the central opening and restrict the gas most adjacent the periphery of the nozzle.

Each of the several burner nozzles disclosed accomplishes a substantially similar result in maintaining the main flame and insuring the effective operation of the burner with gases of various rates of flame propagation.

It will be understood that the nature and embodiments of the invention herein described and illustrated are merely convenient, useful forms of the invention and that many changes and modifications may be made therein without departing from the spirit and scope of the invention.

30. What is claimed is:

1. A burner comprising a nozzle having a main burner orifice for emitting gas at a high velocity, and an elongated auxiliary orifice with a tapering cross-section for producing an auxiliary flame 35 having a gas velocity diminishing progressively

and outwardly between the main burner orifice and the periphery of the nozzle.

2. A burner comprising a nozzle having a main flame orifice, and an auxiliary flame orifice having a uniform length and converging side walls 5 to emit gas at a plurality of velocities ranging between predetermined limits and decreasing with the distance from the main flame.

3. A burner comprising a nozzle having a main flame orifice, and an auxiliary flame orifice of 10 substantially similar length and progressively decreasing cross-section in accordance with the distance from the main flame.

4. A burner comprising a nozzle having a central main flame orifice and a radially extending 15 orifice of progressively greater restriction to emit gas at progressively lower velocities toward the periphery of the nozzle.

5. A gas burner nozzle comprising a series of elongated orifices extending radially from a common center, each of said orifices having tapered side walls for causing delivery of the gas at a plurality of velocities decreasing uniformly with the distance from the center of the nozzle. 20

6. A burner comprising a nozzle having a high 25 gas velocity main burner orifice, and an auxiliary orifice for emitting gas at velocities decreasing uniformly with the distance from the main orifice.

7. A gas burner comprising a cylindrical nozzle, a main gas orifice through the center of the 30 nozzle, and a series of uniformly spaced slots extending radially from the main orifice and having tapered side walls converging at the nozzle periphery.
